UNITED STATES PATENT OFFICE.

BERTHOLD MONASCH, OF BERLIN, GERMANY, ASSIGNOR TO GENERAL ELECTRIC COMPANY, A CORPORATION OF NEW YORK.

ARC-LIGHT ELECTRODE.

1,010,942.

Specification of Letters Patent.

Patented Dec. 5, 1911.

Application filed January 2, 1908. Serial No. 409,040.

To all whom it may concern:

Be it known that I, BERTHOLD MONASCH, a subject of the King of Prussia, residing at Berlin, Germany, have invented certain new 5 and useful Improvements in Arc-Light Electrodes, of which the following is a specification.

My invention has reference to improvements in arc lights and electrodes for the 10 production of flaming arcs.

Metallic oxids that are fairly good conductors in the cold state have heretofore been used as arc electrodes, especially as cathodes, but the metallic oxid which, of all 15 others, has the greatest light-giving power, namely, titanium oxid or rutile, has heretofore been used only sparingly and as an admixture to other oxids or other materials that are fairly good conductors in the cold 20 state. The reason for this sparing use of titanium oxid was the rather high specific resistance of rutile in the cold state, which is so great that this substance is sometimes, although erroneously, spoken of as a non- 25 conductor. I have found, however, that titanium oxid can be used with great advantage as an electrode in an arc lamp without the admixture of other, better conducting materials, if provision is made for 30 establishing the arc; and I have found that by simply inclosing the rutile in a metal tube, and establishing the arc between the metal tube and the other electrode, the arc will promptly shift from the metal sheath 35 to the rutile, and will be maintained without difficulty, especially when a current of higher voltage is employed than has heretofore been deemed commercially practicable. I have obtained excellent results by the use 40 of such electrodes with current having a voltage of 220 volts and the light produced in this manner is whiter, and with the same amount of current, far more intense than when rutile is only employed sparingly as an 45 admixture to other materials.

Where metallic oxids, especially iron oxids, such as magnetite with or without the admixture of rutile, are used in the formation of cathodes, the anodes are preferably 50 made of metal, and I have found that an

iron anode can be advantageously used if made of sufficiently large cross-section so as to have the same degree of heat conductivity as the copper anodes which have heretofore been used; this is especially true when rutile 55 preponderates in the cathode. But with the employment of iron anodes in conjunction with such cathodes a great inconvenience has heretofore been experienced by the freezing together of the anode and the 60 molten pool which forms at the end of the cathode, when the two electrodes come together upon the interruption of the current. In that case there is formed at the junction of the two electrodes an alloy or mixture 65 of the metal oxids of the cathode with the metal of the anode, and when the pool congeals, as it readily does, the two electrodes are "frozen" together, and it has heretofore been found difficult to separate them upon 70 reestablishment of the current.

I have discovered that the alloy or mixture of metal oxid and iron which forms at the junction of the two electrodes is not a thoroughly coherent mass but is more or less 75 honeycombed, and incoherent, and when rutile is the preponderating or sole material of the cathode, the honeycombed junction of the two electrodes has a very high specific resistance, so that upon reestablishment of 80 the circuit, only little current will pass the junction. But I have also found that if a current of much higher voltage than has heretofore been used is employed, sparks will pass through the interstices in the 85 honeycombed alloy, rendering the portions immediately affected conductive, and gradually but rapidly heating the junction until the same melts, so that the ordinary 90 arc-establishing mechanism is now capable of separating the electrodes and establishing the arc. I have found that by the employment of current of 220 v. no difficulty is experienced in separating the frozen electrodes and establishing the arc. 95

By the use of an iron anode in conjunction with any cathode of much smaller diameter, as would be the case when the cathode is made of metal oxids, another difficulty arises from the fact that in the end of the iron 100

anode a crater of considerable depth and rather steep slope is formed. The consequence of this is that when the current is interrupted and the two electrodes come together rather forcibly, the cathode becomes mechanically wedged in the crater of the anode so that it is now quite difficult to separate the electrodes upon reestablishment of the current, irrespective of the freezing together of the electrodes. This difficulty I have overcome by forming the iron anode with a central core of copper or other metal which does not consume as rapidly as the iron, and thus prevents the formation of a deep and steep crater.

My invention therefore embraces an arc electrode formed of titanium oxid without any considerable admixture of other materials, incased in a metal sheath, preferably of iron; it also embraces the combination of such electrode or of any other electrode made principally of metal oxid, as a cathode with an iron anode in a circuit of abnormally high voltage; and it also embraces the combination of a cathode giving a flaming arc, with an iron anode having a central core of copper or other metal which consumes less rapidly than the iron.

In further explanation of my invention, reference is here made to the accompanying drawing, which shows in longitudinal section and in diagram the combination of two arc electrodes in accordance with my invention.

In this drawing 1 is the cathode and 2 the anode. The cathode is constructed with a metal sheath or tube 3, preferably of iron, plugged at the lower end by a piece of wood or other material 4, and having a filling 5 of powdered rutile, or a filling of a mixture of a preponderating amount of rutile with some other metal oxids, especially magnetite. The main body 6 of the anode 2, which has nearly twice the diameter of the cathode, is formed of iron, but has a small core 7 of copper or of any other metal which consumes less rapidly than iron. The arc is primarily established between the upper edge of the metal sheath 3 of the cathode 45 and the iron of the anode, but is very quickly transferred so as to play between the main body of the cathode, which has a preponderance of rutile, and the anode. A molten pool 8 is promptly formed at the working end of the cathode, while the working end of the anode is only very slightly eaten away or depressed, as indicated in solid lines. For all practical purposes the working end of the anode may be considered 50 flat, no crater of any consequence forming at this end, and this is due to the presence of the very slowly consuming core of copper, or other suitable material. In the absence of such core there is formed a steep 55 and deep crater as indicated at 9 in dotted

lines, and when, upon the interruption of the current, the two electrodes come together, the working end of the cathode often wedges tightly in this crater, so that the ordinary arc-establishing mechanism is not powerful enough to separate the electrodes and to reestablish the arc. The core 7 prevents the formation of this crater. But this core does not prevent the freezing together of the electrodes when, upon the interruption of the current, the anode makes contact with the pool 8. When the electrodes thus come in contact a small portion of the metal in the working face of the anode is fused and forms with the pool a 80 honeycombed alloy or mixture of high specific resistance. With the employment of currents of ordinary voltage (110 volts being normally used), the electrodes would remain frozen together, and could not be 85 separated by the ordinary arc-establishing mechanism; but in accordance with my invention, I employ a much higher voltage, up to 220 volts and more, which, discharging between the small interstices of the 90 juncture, forms a number of minute arcs, which rapidly heat and melt the alloy, whereby the ordinary arc-establishing mechanism is enabled to separate the electrodes.

In the drawings I have conventionally 95 indicated clamps or terminals 10, 11 for the electrodes, and conductors 12, 13, leading therefrom to a suitable source of current 14. This latter is represented by the conventional sign for a battery, but is intended to 100 cover any suitable source.

What I claim as new and desire to secure by Letters Patent of the United States, is,

1. An arc light anode of iron having a core of a metal which consumes slower than 105 iron.

2. An arc light anode of iron having a core of copper.

3. The combination in a circuit of abnormally high voltage, of an arc light 110 cathode formed mainly of metal oxid and a substantially iron anode.

4. The combination in a circuit carrying a current of abnormally high voltage, of an arc light cathode formed of a metal tube with a filling in which rutile preponderates, with a metal anode in which iron preponderates.

5. The combination with an arc light cathode formed mainly of metal oxid, with 120 an anode of iron having a greater diameter than the cathode and formed with a core of a metal which consumes slower than iron.

6. The combination of an arc light 125 cathode formed mainly of metal oxid, with an anode of iron having a greater diameter than the cathode and formed with a copper core.

7. An arc light cathode composed sub. 130

stantially of rutile packed in a metal sheath, in combination with an anode of iron having a greater diameter than the cathode and provided with a core of a metal which consumes more slowly than iron.

8. The combination of an arc light cathode, consisting of a metal tube filled with powdered rutile, with an anode composed mainly of iron and having a larger diam-

eter than the cathode, and formed with a 10 copper core.

In witness whereof I have hereunto set my hand this tenth day of December, 1907.

BERTHOLD MONASCH.
